UNITED STATES PATENT OFFICE.

JOHN STROTHER FREEMAN AND WILLIS LEWIS WORTHAM, OF JERSEY CITY, NEW JERSEY, ASSIGNORS TO P. LORILLARD COMPANY, OF NEW YORK, N. Y., A CORPORATION OF NEW JERSEY.

WRAPPING-MACHINE.

1,256,123.

Specification of Letters Patent. Patented Feb. 12, 1918.

Application filed May 21, 1917. Serial No. 169,831.

To all whom it may concern:

Be it known that we, JOHN STROTHER FREEMAN and WILLIS L. WORTHAM, citizens of the United States, and residents of 5 Jersey City, in the county of Hudson and State of New Jersey, have invented certain new and useful Improvements in Wrapping-Machines, of which the following is a specification.

10 This invention relates to wrapping machines, and while we have in the present instance shown it as particularly adapted for the wrapping of small packages, such as boxes of cigarettes, we wish it to be 15 understood that it is not limited in its useful application to this particular purpose, as it may be employed in other connections and under other conditions where its use may be deemed advantageous or desirable. 20 In carrying out our invention it is our purpose to provide a machine through the agency of which an article, such as a package, carton, box or the like may be rapidly and automatically enveloped in a wrapper 25 sheet or cover blank in such manner as to thoroughly protect it against deterioration, soiling and contamination. In this connection, we wish to state that in the wrapping of small packages of goods that are likely 30 to be unfavorably affected by atmospheric influences and changes, such for instance as cigarettes, we prefer to employ wrapper sheets or cover blanks made from transparent or glacé paper so that the boxes or 35 containers will not only be completely and uniformly covered or wrapped so as to present a neat and attractive appearance, while being thoroughly protected against the admission of air and of such foreign substances 40 as might tend to injure or damage the goods, but the boxes themselves may be readily inspected through the transparent wrappers or covers, thus enabling the character and brand of the goods to be determined at a glance by means of the markings, 45 color and other indications appearing on or exhibited by the boxes holding the merchandise.

It is also our purpose to provide a wrapping machine which is automatic and self-contained in the sense that the various steps or stages in the wrapping operation, such as the sequential or successive delivery of

packages into proper position to be wrapped, the application of adhesive or sealing material to the wrapper sheets, the feeding of the wrapper sheets into proper position relative to the packages, the folding and sealing of such sheets about the packages and the final discharge of the latter in completely wrapped and sealed condition is automatically accomplished by a single or unitary machine which requires but little care or attention from the single operator who may be designated to run the machine. 55

Another object of our invention is the provision of a machine of this character wherein great quantities of packages or boxes may be economically, speedily and efficiently wrapped, and which machine may be installed and operated at a relatively low cost. 60

With the above recited objects and others of a similar nature in view, our invention consists in the construction, combination and arrangement of parts set forth in and falling within the scope of the appended claims. 75

In the accompanying drawings,

Figure 1 is a front elevation of a preferred form of wrapping machine embodying our invention, certain of the parts being 80 broken away.

Fig. 2 is a top plan view thereof.

Fig. 3 is a transverse vertical sectional view taken through the machine approximately centrally thereof. 85

Fig. 4 is a view partly in section and partly in elevation, showing the traveling carriage carrying the plungers in position adjacent to the adhesive or glue supplying device. 90

Fig. 5 is a view partly in top plan and partly in section of the mechanism for delivering the unwrapped packages from the magazine to the carriage. 95

Fig. 6 is a top plan of the carriage and parts carried thereby and showing the same positioned in operative relation to the magazine to receive a package therefrom. 100

Fig. 7 is a view partly in side elevation and partly in section taken through the carriage and its immediate supporting parts and illustrating the wrapper carrying plunger in position to descend upon the stack of wrappers, certain parts being omitted for the sake of clearness. 105

Fig. 8 is a similar detail view and illus-

trating the plunger in engagement with the stack of wrappers and about to remove the uppermost wrapper therefrom.

Fig. 9 is a detail perspective view showing a stack of wrapper sheets on their support together with the devices for maintaining the sheets in proper stacked alinement.

Fig. 10 is a detail view in elevation, showing the upper portion of the forming well and illustrating one step preparatory to the folding of the wrapper about the package.

Fig. 11 is a detail view partly in section showing a step in the folding of the wrapper about the package.

Figs. 12, 13 and 14 are detail views showing the successive steps in the folding of the wrapper about the package.

Fig. 15 is a perspective view showing a completely wrapped and sealed package.

Before entering into a detailed description of our invention, we will briefly state that in the form shown herein it embraces among other features a traveling carriage on which is mounted a package magazine in which the operator places a stack or pile of the packages to be wrapped, such as boxes of cigarettes, the duty of the operator being to replenish the supply in the magazine as may be necessary. The lower end of the magazine opens into a chamber in which reciprocates a pusher block which takes the lowermost package from the magazine and pushes it into a carrier head mounted on the traveling or reciprocating carriage. This carrier head is also provided with a suitable number of glue pads, which, when the carriage moves in one direction, in the present instance toward the left as shown in Figs. 1 and 2, are brought into contact with suitable wallower rollers working in a bath of glue in a glue tank, the glue or adhesive being thus applied to the pads. As the carriage moves away from the glue tank, or toward the right, these glue pads are brought into contact with and pick up the top sheet from a stack or pile of wrapper sheets mounted upon a suitable self-adjusting support. As the carriage continues its movement toward the right of the machine, considering Figs. 1 and 2, the before mentioned carrier head, now holding a package to be wrapped, and a wrapper sheet which is held by the glue pads directly beneath the package, is brought to position above a forming well. This well is preferably in the nature of a box-like casing or chute, the upper portion thereof being vertical or straight while the lower portion is curved in the form of an elbow to constitute a relatively long passageway to a point of discharge, the chute being preferably so constructed for the purpose of causing the packages to take a long, slow path of travel, thus permitting the drying of the glue on the sealed wrappers.

When the carrier head arrives over the up-

per end of the forming well the box and wrapper are forced by a plunger moving in the carrier head into the forming well, thus folding the wrapper ends up about the two sides of the box, as will be understood by reference to Fig. 11. A pair of oppositely moving folding plates now fold the free ends of the wrapper inward over the top of the box, as will be understood by reference to Fig. 12, with the two end portions of the wrapper projecting from opposite ends of the box. The ends of the wrapper are then folded or tucked in by folding fingers, as shown in Fig. 13, after which, in due course, the overlapping portions on top of the box are folded downward by a plunger-like reciprocating folding head, as illustrated in Fig. 14. Then as the box is subsequently forced down into the folding well the remaining outstanding portions of the wrapper are folded upward and pasted to the previously folded portions at the ends of the boxes so that the completely covered and wrapped box will appear as shown in Fig. 15. The completely wrapped and sealed boxes then pass down the delivery chute as shown in Fig. 1.

Referring now to the accompanying drawings in detail, and particularly to Figs. 1, 2 and 3, the letter A indicates the frame 95 of the machine which includes the bed or table B and the back wall C. The power shaft of the machine is indicated by the numeral 1 and is mounted in suitable bearings 2 at the rear of the frame A. This shaft 1 is 100 provided at one end with the usual fast pulley 3 and the loose pulley 4, the shaft of course being adapted to be driven, as will be well understood, by a belt running over the pulley 3 and which belt may be 105 shifted as desired to the pulley 4, to throw the machine out of operation. On the power shaft 1 is a gear pinion 5 which meshes with and drives the large gear wheel 6 on the cam shaft 7 which extends approximately parallel with and above the power shaft 1 at the rear of the frame, this shaft being mounted in suitable bearings 8. On this cam shaft 7, and at approximately the center thereof is mounted the large drum cam 115 9 having the circumferentially extending eccentric cam groove 10 into which projects the stud 11 carried by the carriage shifting arm 12 which reciprocates or shifts the carriage D, as will be hereinafter understood. The lower end of the arm 12 terminates in a sleeve 13 mounted to rock on the stud shaft 14 carried by the back wall of the frame and the upper end of this arm 12 is connected through a suitable flexible or link 125 coupling 15 with the stud 16 extending from the back of the carriage D, as will be readily understood by reference to Figs. 3 and 7, so that when the drum cam 9 is revolved a reciprocating sliding motion will be im- 130

parted through the arm 12 to the carriage D. To permit of this we provide the back wall C of the frame with a pair of spaced parallel tracks or guides 17, the grooves 18 of which receive the parallel tapered flanges 19 of the carriage, these flanges fitting loosely in the grooves so as to permit of the free sliding movement of the carriage.

Suitably supported by and traveling with the carriage is a hopper or magazine E, which in the present instance is of rectangular or box-like form to receive the packages F which are to be wrapped, and which in the present instance may be considered as boxes of cigarettes. The lower end of the magazine E opens into a shallow elongated chamber 20 in which reciprocates a pusher block 21. When the pusher block is positioned in the forward extension 22 of the chamber 20, there will be no support to prevent the dropping of the packages F to this chamber 20, and consequently the lowermost package will descend into this chamber and rest upon the bottom or floor rails of the latter, as will be understood by reference to Figs. 3 and 5. However, when the pusher block 21 is shifted rearward of the machine, or from the extension 22 of the chamber to a position directly beneath the magazine, it will take the bottom package which we have shown at F' in said Figs. 3 and 5 and push the same into the carrier head 23 which partially forms a rear section or continuation of the chamber 20, and in which is reciprocated a plunger for forcing the package out of the head as will be seen by reference to Fig. 4, and which will be hereafter described in detail.

In order to reciprocate the pusher block 21 to accomplish the feeding of the packages from the magazine to the carrier head 23 as just described we secure a cam strip or bar 24 to the front face of the back wall C of the frame, as will be understood by reference to Fig. 2, this strip being preferably in the nature of a thin flexible bar of metal, such as steel, and for a portion of its distance it is inclined outwardly relative to the back wall of the frame, and then near its outer end extending substantially parallel with such back portion of the frame and is connected therewith by a short rod, as shown at 24'. As will be seen by reference to Fig. 5, this cam strip guides the bracket 26 which has a pair of rollers 27 which embrace the cam strip. This bracket in turn forms a connection with the sliding yoke 28 of the pusher block, the parallel arms 29 of the yoke projecting through openings 30 in the end of the carrier head and slide in grooves 31 in the side bars 32 of the head as will be understood by reference to Fig. 4, these yoke arms 29 being connected with or form a part of the sides of the pusher block 21. Furthermore, these yoke arms 29 are longitudi-

nally slotted as at 33 and through these slots project short pins 34 carried by leaf springs 35; the pins thus yieldingly engaging the sides of the package to assist in maintaining the latter properly positioned in the carrier head and beneath the plunger thereof. As the bracket 26 slides along the cam strip 24, with the travel of the carriage a sliding movement is imparted to the pusher block 21, the block moving toward the back of the machine to place the package in the carrier when the carriage is moving toward the right in Fig. 1, said block moving in the reverse direction or toward and into the chamber extensions 22, when the carriage is traveling toward the left. When the package is pushed into the carrier head it rides over and rests upon the yieldingly mounted spring-tensioned plates 36 which while they are horizontally positioned support the package and prevent its falling from the carrier, but will under pressure exerted by the plunger G against the package yield downward to permit the latter to escape, as shown in Fig. 10. As will best be seen by reference to Figs. 1 and 10 at 37 is shown a stop and guide for one end of the package and 38 shows an adjustable stop and guide for the other end of the package, these stops 37 and 38 also serving to position the wrapper sheet as will hereafter appear. The wrappers are shown at P, and are preferably in the nature of rectangular sheets of transparent or glacé paper, especially when intended for the wrapping of cigarette boxes, and in Fig. 9, we have shown a stack of such wrappers positioned on a table or support 39 mounted on the upper end of the post 40. In order to insure that the top wrapper of the stack will always be in proper position to be withdrawn for application to a package, irrespective of the decrease in the thickness of the stack of wrappers when the machine is in use, we provide for the automatic and intermittent or step by step elevation of the wrapper support or table, by forming a longitudinally extending flat face 41 on the post 40 against which bears a clamping pin 42 mounted on a small rocking stud 43, rocking in the sleeve 44 of the post block or bearing 45, the post passing through a vertical bore 46 in this bearing. The rocking stud 43 is carried by an arm 47, the outer end of which is pivoted at 48 to a shank 49 which extends vertically to the bore 50 in the free end of the cam lever 51. This lever 51 is fulcrumed at 52 and at its rear end carries a cam roller 53 which rides in the groove 54 of the cam disk 55 on the cam shaft 7. At the proper time in the rotation of the cam 55 the forward or free end of the cam lever 51 is elevated striking the head 49' of the shank 49 and which head in the present instance comprises a pair of nuts, and lifting up on the shank 49 will rock the stud 43 to mo-

mentarily withdraw the clamping pin from contact with the flat face 41 of the post 40, and as the lower end of the post is linked as at 56 to the hand lever 57 pivoted at 58 on the frame A, the adjustable weight 59 at the rear end of the lever will exercise power to push upward on the post 40 and thus elevate the stack support. The continued movement of the cam 55 will move 10 the lever 51 downward away from the head of the shank 49 and the spring tensioned stud 60 connected with the arm 47 between the rocking stud 43 and the shank 49 will immediately act on this arm 47 and pull the 15 same downward to cause the clamping pin 42 to again engage the post 40 and hold the stack support stationary against the influence of the weight 59. In other words every time the clamping pin 42 moves away from 20 the post 40 the latter will be shifted upward by the action of the weight 59 while with the restoration of the clamping action of the pin 42 the post with the stack support will be clamped against movement. When it is de- 25 sired to completely lower the stack table or support, as when placing a new stack of wrappers thereon, the operator may grasp the handle 57' of the hand lever 57 and depressing the handle against the action of the 30 weight 59, may lower the table, or support, as will be obvious.

For the purpose of maintaining the wrappers in an even, alined stack on the support, any suitable guides or confining devices may 35 be employed. In the present instance we employ a vertically disposed angular corner guide 61 which is fastened at its foot to the table of the frame, and at its upper end embraces one corner of the stack of wrappers 40 as shown in Fig. 9, the top of this corner guide 61 terminating in a lip 62 which overlies the top of the wrapper and is inclined upward so as not to interfere with the removal of the individual wrappers from the 45 stack. To prevent more than one sheet of wrapper being taken from the stack at one time we preferably provide a front clamping finger 63, the free angular end 63' of which engages the top of the stack of wrappers, as shown in Fig. 9. This clamping finger 63 is mounted upon a rod 64 and is tensioned by means of the coil spring 64' so that the spring tends to normally throw the ends 63' of the finger into clamping position. When the operator desires to replenish 50 the stack, the clamping finger 63 may be grasped and swung out of the way, by swinging the rod 64, because this rod 64 is socketed in a swinging sleeve 65, the upper 55 end of which is formed with a pintle 66 journaled in the bracket lug 66^a on the corner guide 61, while the lower end of such sleeve which is supported in the bracket lug 66^b terminates in an eccentric 65' to which 60 65 is connected one end of a sliding rod 67

tensioned by the expansion spring 67', this rod sliding through small bracket lugs 68', the rearmost of these lugs 68' being carried by the corner plate 68 which is mounted upon the bed B. As will be understood by 70 reference to Fig. 2, the rod 64 in its normal position when holding the clamping finger in engagement with the stack of leaves is maintained in such position by the spring tensioned rod 67. However, if it is desired 75 to replenish the stack and this rod 64 is swung outward, the expansion spring 67' will be contracted until the eccentric 65' is swung over the dead center, when the pull on the rod 64 may be released and the swing 80 having expanded, the rod with the clamping finger will be held in its open position away from the stack. To restore the parts to clamping position, it is only necessary to swing the rod 64 toward the stack and over 85 the dead center again and the action of the spring 67' will throw the rod with the clamping finger into clamping position. At the opposite side of the stack of wrappers there is located a vertical guide bar 69, the 90 foot of which is fastened to the bed B of the frame and the upper end 70 of which lies against and forms an alining guide for the adjacent side edges of the wrappers. An angular strip 71 is fastened to this bar 95 69 and extending toward the rear of the stack terminates in a short lip 72 which slightly engages the stack of wrappers near the adjacent corner end. The bar 69 near its upper end is formed with a rib 73 which 100 is centrally recessed as at 74 to receive the lower end of the rocking tongue 75, this tongue being mounted to rock with the movement of the crank rod 76 journaled in the rib 73. This crank rod is rocked 105 through a link rod 77, the lower end of which is connected at 78 with the rock arm 79 carried by the rock shaft 80 journaled in the bracket 81 depending from the frame, this shaft being rocked from the cam shaft 110 7 through the cam 82, cam lever 83 and link 84 which is connected to the opposite end of the shaft 80, from that which the arm 79 is connected. Thus with every revolution 115 of the cam, at predetermined times, the tongue 75 will be rocked to and from the side of the stack, this tongue 75 carrying an angular wire finger 85 which will knock or strike against the side of the wrapper stack with the proper movement of the 120 tongue 75 and will act as a jogger to assist in keeping the sheets of the stack in alinement. A leaf spring 86 tends to throw the tongue 75 toward the wrapper stack and the tongue is moved away from the stack by the cam mechanism against the action of this leaf spring at the time each top wrapper is being removed from the stack by the glue pads which form a part of the glue or adhesive applying mechanism. 125 130

Thus by the various guides or alining devices just described the sheets are maintained in proper stacked alinement and yet are so held as not to interfere with the selection and removal of individual sheets at proper times.

We will now proceed to briefly describe the gluing or adhesive applying devices and the functions performed by the same. The letter J indicates a glue tank in which works a wallower or glue supplying roll 87 which is mounted on the shaft 88 driven through the beveled gearing 89 and shaft 90, the latter shaft in turn having a pulley 91 driven by the belt 92 from the pulley 93 on the power shaft 1, so that through the train of power transmitting mechanism just described, the wallower roll 87 may be rotated in the bath of glue shown at K in Fig. 4, thereby insuring a constant supply of fresh glue to the surface of the roll 87. The same shaft which carries the glue roll 87 also carries a small glue supplying disk 87', and the shaft may be set or adjusted to properly adjust the glue roll 87 and disk 87' lengthwise of the tank a slight distance, by means of the screw rods 94 connected with the shaft bearing. Any suitable arrangement, however, may be employed for properly positioning the glue roll and disk in the tank.

Referring to Figs. 4, 7 and 8, it will be seen that the carriage is formed with a bracket 95 which includes a cross head 96 having an opposite side thereof, a pair of sleeves 97 through which slide bars 98 having attached to their lower end glue pads 99 which lie relatively to each other at opposite sides of the carrier head containing the package as will be clearly understood by reference to Fig. 4.

These bars 98 carrying the glue pads are longitudinally recessed or cut away as at 100, and these cut-away portions of the bars work through the slots 101 in the cross bar 102, the shank 103 of which carries at its rear end the block 104 adapted to vertically slide or reciprocate in the slot 105 formed in the frame of the carriage, as will be seen by reference to Fig. 7. The shank 103 carries the oppositely extending stud shafts 106, and at the end of each of these stud shafts there is mounted a rocking bar 107; the forward end of each of these bars extends into the recess 100 of the adjacent glue pad carrying bar 98, while the opposite or rear end of each of these bars 107 lies beneath the limiting bolt or stop 108. It will be noted by reference to Fig. 7, that the forward end 107 of each bar 107 lies between the shoulder at the upper end of the recess in the bar 99 and the rear edge portion of the cross bar 102 so that this bar 107 at its forward end will have but a limited rocking motion. The cross bar 102 is fast with the sleeve 109 sliding on the post 110, the foot of which

post is set on the top of the carrier head of the package. This sliding sleeve 109 is formed with a head 111 from which projects the oppositely extending studs 112, these studs being connected with arms 113 extending rearwardly of the machine and fulcrumed on the shaft 114 mounted in the web brackets 115 of the sliding carriage. Integral with and extending rearward from the arms 113 is an arm 116 pivotally connected with a block 117 slidably mounted in the groove 118 of a rocking slide 119, the latter being journaled at its ends as at 120, as shown in Fig. 1. This slide 119 is rocked through the cam lever 121 connected at one end with the yoke arm 122 at the back of the slide, the opposite end of this cam lever terminating in the usual cam fork 123 carrying the cam roller 124 operated by the cam disk 125. Thus, as the slide 119 is rocked up and down from the cam shaft 7 through the connection just described, the sleeve 109 will be given a corresponding vertically reciprocating movement on the post 110. It will be noted by reference to Figs. 3 and 7 that the block 104 at the end of the shank 103 has socketed therein the upper end of the stem 126 of the glue applying stencil 127, the head 128 of which is best shown in Fig. 9 and is adapted to apply a stripe of glue to the rear transverse edge of each top wrapper of the stack at predetermined times, and simultaneously with the application of glue to the side edges of a wrapper by the glue pads 99, as will be understood by reference to Fig. 8. Now in the operation of the machine the carriage first travels to the left of the machine, considering Fig. 1, which brings the glue pads 99 and the head 128 of the glue stencil 127 over the glue tank and into contact with the glue wallower roll 87 and the glue supplying disk 87' respectively so that the two glue pads 99 receive a supply of glue from the roll 87 as they slide across the top of the latter and in like contact therewith as will be understood by reference to Figs. 3 and 4, while the glue stencil head 128 receives this glue from the glue disk 87'. At this time it should be understood that the carriage with the glue pads and stencil is to one side, or to the left of the stack of wrappers and that such pads and stencil are in an elevated position, or in a plane higher than the stack of wrappers, as will be understood by reference to Fig. 7, the glue tank with its roller and disk being of course so adjusted as to give proper contact with the pads and stencil respectively when the latter are moved thereover to receive the glue. After the pads and stencil have been supplied with glue, the carriage starts its retractive movement or its travel toward the opposite side of the machine and when it reaches the position over the stack of wrappers, the down-

ward movement of the sleeve 109 on the post 10 causes the shank 103 and its cross bar 102 to be lowered a short distance thus lowering pads 99 and stencil 128 simultaneously into contact with the top sheet of the stack. The bars 98 carrying the glue pads will be lowered because while sliding in the sleeve 97 they will travel with the head 102 due to the fact that each bar has connected thereto, at 130, a contraction spring 131, the lower end of which is connected at 132 to the sleeve through which the bar slides, and consequently the tendency of the spring is to lower or pull the bar and the glue pad downward. However, the end 107' of the rocking bar 107 projecting into the recess 100, acting in conjunction with the pivoted latch 133, will prevent the downward movement of the bar 98, independently of the cross head 102, except at the time hereinafter described, a leaf spring 134 normally pressing the latch 133 into locking position beneath the front edge of the cross head 102, as shown in Fig. 7. Therefore, with the depression of the sleeve 109, the glue pads 99 and the glue stencil 128 engage with the top sheet of the stack, and when the cross head 102 has reached the limit of its downward movement under the action of the sleeve 109, the rounded shoulder of the latch head 135 hits the pin 136 and the latch moves outward against the action of the leaf spring 134 as shown in Fig. 8, causing the bar 98 to be pressed or pulled sharply downward a short distance by its spring 131 thereby pressing the pad 99 firmly into contact with the top sheet of paper, so that when the pad is again elevated the top sheet will be lifted along by it. Of course at the same time the glue stencil has applied a stripe of glue to the rear transverse edge portion of the sheet. After thus gluing and engaging the top wrapper of the stack, the glue pads are lifted with such wrapper because the slide 119 starts to rock in the opposite direction under the action of its operating cam, the carriage continuing its travel of course and the result is that the sleeve 109 will be moved upward on the post 110 carrying with it the cross head 102 and of course the shank 103 with the rocking arm 107. When the rear end of the arm 107 strikes against the bolt shank or stop 108, its forward end 107' will engage beneath the adjacent shoulder of the bar 98 and lift the bar bodily so as to permit the latch 133 to drop back into latching position shown in Fig. 7, thus holding the glue pad 99 in its normal elevated position, and with the wrapper sheet carried thereby and lying beneath the box in the carrier head.

The continued movement of the carriage toward the right of the machine as illustrated in Fig. 1, now brings the package and the wrapper sheet directly over the forming

well 137, as shown in Fig. 10, this forming well being in the nature of a vertically disposed box-like chute, the lower portion of which terminates in an elbow 138 through which the wrapped packages pass to a suitable point of discharge. When the carriage has brought the package and wrapper to the position shown in Fig. 10, the spring tensioned stem 139 of the plunger 140 of the carrier head is brought directly beneath the 70 rocking pusher arm 141 which is fulcrumed as at 142 on the top of the wall C of the frame and is rocked up and down by a cam lever 143 actuated from the cam 144 on the shaft 7. When the free end 141' of this lever 141 is moved down against the roller 139' at the upper end of the stem 139 it depresses this stem against the action of the spring 146, and the plunger 140 striking the package, pushes the same out from the carrier head past the plates 36, which are forced open to permit the passage of the package and the latter is forced into the mouth of the forming well, carrying with it the wrapper sheet so that the latter is folded about the 80 bottom and two opposite sides of the package by the walls of the well, as shown in Fig. 11.

By reference to Figs. 4 and 6, it will be seen that the traveling carriage has rigid therewith a laterally extending bracket 147 which extends in the present instance to the right side of the carrier head in which the package is transported, and that sliding in the vertical section 148 of this bracket is a 100 stem 149 tensioned by a spring 150 and carrying at its lower end a plunger plate 151 which lies beneath the flanged folding head 152 tensioned by the spring 153 and carried by its sleeve 154 through which the 105 stem 149 passes. At the time the package is positioned as shown in Fig. 11, the stem 149 and the parts operated thereby lie to the right side of the forming well or in operative position. Now as the carriage with the carrier head starts its retractive motion or toward the left of the machine after delivering the package and wrapper to the forming well, as shown in Fig. 11, two oppositely acting folding plates 155 mounted on top of 110 and projecting beyond tuck-in fingers 156 are brought into operation to fold over the top flaps of the wrapper f, as indicated in Fig. 12 and then after these flaps have been folded down the tuck-in fingers 156, of 120 which there are four, fold in the corner laps of the package, as shown in Fig. 13. Of course the folding plates 155 and the tuck-in fingers 156 on which the plates are mounted, are operated in proper timed relation, or directly after the plunger of the carrier head has forced the package and the wrapper into the forming well, as shown in Fig. 11. The tuck-in fingers 156 carrying these plates 155 are operated through suitable links 157 ac- 130

5 tuated from cam rods 158 which in turn are operated by the cams 159 on the shaft 7, and is to be understood that these tuck-in fingers may be of any well known form. After the 10 tucking in of the corner laps, the return movement of the carriage brings the stem 149 beneath the presser arm 141, and the latter being again depressed, strikes the upper end of the stem and causes the flanges 152' 15 of the folding head 152 to fold down the side flaps f^2 of the wrapper, as shown in Fig. 14. At this time the carrier head is receiving another box, and the carriage continuing its travel toward the left, the glue 20 pads receive another supply of glue. Then as the carriage starts toward the right of Fig. 1 on another trip, and with another box, as it reaches its position to take the wrapper, the stem 149 is of course again brought beneath the arm 141, and the latter being depressed this time, forces the stem 149 downward, and this movement, shifts the plunger 25 plate 151 from the position shown in full lines in Fig. 4, to that shown in dotted lines in said figure, thus pushing the nearly completely wrapped package of Fig. 14 down into the chute and the rollers 160 at opposite sides of the chute, contacting with the bottom side flaps f^3 will fold the latter up 30 over the laps f^2 , and the package will be sealed as shown in Fig. 15, the adhesive or glue stripes of course causing the adherence or sealing of the various flaps of the wrapper.

35 The operation of the machine is successive and continuous, the various steps of feeding, folding and the like taking place in proper sequence and in proper timed relation. The tab f^4 of the package may be provided on one 40 of the top flaps to permit the easy and ready opening of the package.

45 While we have herein shown and described one particular embodiment of our invention, we wish it to be understood that we do not confine ourselves to all the precise details of construction herein set forth by way of illustration, as modification and variation may be made without departing from the spirit of the invention or exceeding the scope of the appended claims.

50 What we claim is:

55 1. In a wrapping machine, a traveling carriage, a package magazine mounted on the carriage, a box support movable with the carriage, and means for automatically removing a package from the magazine and delivering said package to the box support during the travel of the carriage.

60 2. In a wrapping machine, a traveling carriage, a package magazine mounted on and movable with the carriage, a box support also movable with the traveling carriage, and a reciprocating device also movable with the carriage for automatically 65 moving a package from the magazine and

delivering said package to the box support at certain times during the travel of the carriage.

3. In a wrapping machine, a package magazine having a chamber at its lower end adapted to receive packages one at a time from the body of the magazine, a support for a stack of wrappers, a traveling package support arranged in alinement with the chamber of the magazine, means operating in the chamber for automatically removing a package therefrom and delivering the same to the package support, a support for a stack of wrappers, means moving with the package support for removing a wrapper from the stack and holding the same in position for application to the package, instrumentalities for folding the wrapper about the package, and means for transferring the wrapper and package from their respective supports to the folding instrumentalities.

4. In a wrapping machine, the combination of a traveling carriage, a package magazine carried thereby and having a chamber at its lower end adapted to receive packages singly from the magazine, a support for a stack of wrappers, a traveling package support on the carriage and in alinement with the chamber of the magazine, means operating in the chamber for automatically removing a package therefrom and delivering the same to the package support, means moving with the package support for removing a wrapper from the stack and holding the same in position for application to the package, instrumentalities for folding the wrapper about the package, and means for transferring the wrapper and package from their respective supports to the folding instrumentalities.

5. In a wrapping machine, the combination with a traveling carriage, of a package magazine mounted thereon, means on and traveling with the carriage for supporting a package, means also mounted on the carriage for holding a wrapper in a predetermined position relative to the package, wrapper folding instrumentalities for folding the wrapper about the package, and means for automatically transferring the package and positioned wrapper to the folding instrumentalities.

6. In a wrapping machine, the combination with instrumentalities for folding a wrapper about a package, of a traveling carriage, a package support on the carriage, means for automatically feeding packages one at a time to said support during the travel of the carriage, means on the carriage for holding a wrapper in a predetermined position beneath a package on the package support, and mechanism for automatically transferring the package and the positioned wrapper to the wrapper folding instrumentalities.

- 8
7. In a wrapping machine, the combination with a magazine, of a traveling support for horizontally supporting a package to be wrapped, means for automatically feeding packages one at a time from the magazine to the support, means mounted beneath the package support and movable therewith for applying an adhesive to a wrapper and holding said wrapper in registered position beneath a package on the support, means for folding the wrapper about the package, and means adapted to deliver the registered package and wrapper to the wrapper folding means.
15. 8. In a wrapping machine, the combination with a magazine and a traveling package support, of means for automatically feeding a package from the magazine to the support, a support for a stack of wrappers, an adhesive supplying mechanism, means carried by the traveling support for receiving adhesive from the adhesive supplying mechanism and for engaging a wrapper on the wrapper support and moving said wrapper to a position of registration beneath a package on the traveling support, means for folding the wrapper about the package, and means for delivering the box and wrapper from the traveling support to the folding means.
30. 9. In a wrapping machine, the combination with a traveling magazine and a traveling package support for horizontally supporting a package to be wrapped, of reciprocating means for automatically feeding packages one at a time from the magazine to the package support, means for holding a wrapper in registered position beneath a package on the support, said wrapper holding means traveling with the support, wrapper folding means, and a plunger for delivering the package and wrapper from the traveling support to the folding means.
45. 10. In a wrapping machine, the combination with a package magazine and a support for a stack of wrappers, of a traveling carriage, package supporting means on the carriage, means for automatically delivering a package to the package supporting means during the travel of the carriage, adhesive supplying means, devices on the carriage adapted to receive a supply of adhesive from the supplying means, and to engage a wrapper on the support to apply adhesive to the wrapper and to remove the wrapper from the support and hold the same in registered position beneath the package supporting means, folding means, and means operable to deliver the registered package and wrapper to the folding means.
55. 11. In a wrapping machine, a traveling carriage, box supporting means thereon, means traveling with the carriage for automatically feeding boxes one at a time to the box supporting means, and means also mounted on the carriage for applying an adhesive to a wrapper and for holding said wrapper in registered position with a box on the box-supporting means.
65. 12. In a wrapping machine, a package magazine, a traveling carriage, box-supporting means mounted thereon, means traveling with and reciprocating during the movement of the carriage for automatically delivering boxes from the magazine to the box support on the carriage, and means for automatically applying adhesive to wrappers and holding said wrappers in registered position with boxes on the box-support.
70. 13. In a wrapping machine, a traveling carriage, yielding box supporting means mounted thereon, means traveling with the carriage for automatically delivering a box to the box support during the travel of the carriage, means also mounted on the carriage for automatically applying adhesive to a wrapper and holding said wrapper in registered position with a box on the box support, wrapper folding instrumentalities, and means adapted at predetermined times to remove the box from the support and deliver it with the wrapper to the folding instrumentalities.
75. 14. In a wrapping machine, a traveling carriage, a package magazine, a box support movable with the traveling carriage, means traveling with the carriage for automatically removing a package from the magazine and delivering said package to the box support during the movement of the carriage, adhesive supplying means, devices mounted on the carriage adjacent the box support adapted to receive adhesive from the supplying means and to apply said adhesive to a wrapper and to hold said wrapper in registered position with the package on the box support, wrapper folding means, and a plunger adapted to remove the package from the box support and deliver said package with the wrapper to the folding means.
80. 15. In a wrapping machine, a support for a stack of wrappers, a traveling carriage, a box support on the traveling carriage, means traveling with the carriage for automatically feeding the box to the box support during the movement of the carriage, glue pads located adjacent the box support and traveling with the carriage adapted to apply glue to a wrapper of the stack and to carry said wrapper from the stack into a position of registration with a box on the support, wrapper folding means, and means for removing the box from its support and delivering the same with the registered wrapper to the wrapper folding means.
85. 16. In a wrapping machine, the combination with an adjustable support for a stack of wrappers, of means for maintaining the wrappers of the stack in stacked alignment
90. 95. 100. 105. 110. 115. 120. 125. 130.

- on the support, a magazine for packages, a traveling carriage, a package support on the traveling carriage, means for automatically feeding packages from the magazine to the support on the carriage, adhesive-supplying means, an adhesive applying stencil mounted on the carriage adjacent the package support and adapted to receive adhesive from the supplying means and to apply the same to the uppermost wrapper of the stack, means for operating the stencil to lift the wrapper from the stack and hold said wrapper in registered position with the package on the support, a forming well, a plunger for forcing the package from the support on the carriage and delivering the same to the forming well where said wrapper is folded about the bottom and two sides of the package, and wrapper folding instrumentalities located at the well. 60
- 5 17. In a wrapping machine, the combination with an adjustable support for a stack of wrappers, of guiding members for maintaining the wrappers of the stack in stacked alinement on the support, a magazine for 15 the package, a traveling carriage, a package support on the traveling carriage, a reciprocating pusher block for feeding packages from the magazine to the support on the carriage, means including a cam bar 20 and sliding connections between the cam bar and the pusher block for reciprocating the latter at predetermined times, adhesive supplying rollers, adhesive applying stencils mounted on the carriage adjacent the package support, and adapted to receive adhesive from the supplying rollers and to apply the same to the uppermost wrapper of the stack, means for operating the stencils to lift the wrapper from the stack and hold such 25 wrapper in registered position with a package on the support, a forming well, a plunger for forcing the package from the support on the carriage and delivering the same to the forming well, and wrapper folding 30 instrumentalities located at the well operating to fold the wrapper about the package. 35
18. In a wrapping machine, the combination with an adjustable support for a stack of wrappers, of guiding members for maintaining the wrappers of the stack in stacked alinement on the support, a magazine for packages, a traveling carriage, a package support on the traveling carriage, a reciprocating plunger for automatically feeding 40 packages from the magazine to the support on the carriage, adhesive-supplying rollers, adhesive applying stencils mounted on the carriage adjacent the package support and adapted to receive adhesive from the supply- 45
- ing rollers and to apply the same to the uppermost wrapper of the stack, means for operating the stencils to lift the wrapper from the stack and hold said wrapper in registered position with the package on the support, a forming well, a plunger for forcing the package from the support on the carriage and delivering the same to the forming well where said wrapper is folded about the bottom and two sides of the package, and wrapper folding instrumentalities 50 located at the well. 65
19. In a wrapping machine, the combination with a support for a stack of wrappers, clamping means for holding said wrappers in stacked alinement while permitting the removal of single wrappers from the stack, a traveling carriage having a package support, a magazine for the packages to be wrapped, a reciprocating pusher member for pushing the packages one at a time 60 from the magazine to the package support on the carriage, an adhesive applying device on the carriage, means including a vertically movable member and a rocking device for moving the adhesive applying device into contact with the uppermost wrapper on the wrapper support to remove said wrapper from the stack and position the same relative to the package in the carriage, instrumentalities for removing the package 65 and wrapper from the carriage and folding the wrapper about the package, and means for restoring the adhesive applying devices to normal position. 70
20. In a wrapping machine, the combination with a traveling support, of a magazine for containing packages to be wrapped, a reciprocating pusher block for feeding the packages from the magazine to the support, a support for a stack of wrappers, adhesive 75 supplying mechanism including a container for the adhesive and a roller working therein, a stencil carried by the traveling support for receiving adhesive from the roller and for engaging the wrapper on the 80 wrapper support and moving the wrapper to a position of registration with the package on the traveling support, a forming well, a plunger for forcing the package and wrapper from the carriage into the forming well, 85 and wrapper folding instrumentalities located at the well. 90
